[57] CLAIM

The ornamental design for a combined nail storage and display rack, as shown.

DESCRIPTION

FIG. 1 is a perspective view of a combined nail storage and display rack showing my new design;
FIG. 2 is a front view thereof;
FIG. 3 is a side view taken from the right of FIG. 2, the side opposite thereto being a mirror image thereof;
FIG. 4 is a rear view thereof;
FIG. 5 is a top plan view thereof; and
FIG. 6 is a bottom view.
